CLAIM

The ornamental design for a nasal dilator, as shown and described.

DESCRIPTION

FIG. 1 is a three-quarter perspective view of a first embodiment of a nasal dilator;
FIG. 2 is a perspective view thereof, shown in a state of use;
FIG. 3 is a top plan view thereof;
FIG. 4 is a three-quarter perspective view of a second embodiment of a nasal dilator;
FIG. 5 is a perspective view thereof, shown in a state of use;
FIG. 6 is a top plan view thereof;
FIG. 7 is a three-quarter perspective view of third embodiment of a nasal dilator;
FIG. 8 is a perspective view thereof, shown in a state of use;
FIG. 9 is a top plan view thereof;
FIG. 10 is a three-quarter perspective view of a fourth embodiment of a nasal dilator;
FIG. 11 is a perspective view thereof, shown in a state of use;
FIG. 12 is a top plan view thereof;
FIG. 13 is a three-quarter perspective view of a fifth embodiment of a nasal dilator showing;
FIG. 14 is a perspective view thereof, shown in a state of use;
FIG. 15 is a top plan view thereof;
FIG. 16 is a three-quarter perspective view of a sixth embodiment of a nasal dilator;
FIG. 17 is a perspective view thereof, shown in a state of use;
FIG. 18 is a top plan view thereof;
FIG. 19 is a three-quarter perspective view of a seventh embodiment of a nasal dilator;
FIG. 20 is a perspective view thereof, shown in a state of use;
FIG. 21 is a top plan view thereof;
FIG. 22 is a three-quarter perspective view of an eighth embodiment of a nasal dilator;
FIG. 23 is a perspective view thereof, shown in a state of use;
FIG. 24 is a top plan view thereof;
FIG. 25 is a three-quarter perspective view of a ninth embodiment of a nasal dilator;
FIG. 26 is a perspective view thereof, shown in a state of use;
FIG. 27 is a top plan view thereof;
FIG. 28 is a three-quarter perspective view of a tenth embodiment of a nasal dilator;
FIG. 29 is a perspective view thereof, shown in a state of use;
FIG. 30 is a top plan view thereof;
FIG. 31 is a three-quarter perspective view of an eleventh embodiment of a nasal dilator;
FIG. 32 is a perspective view thereof, shown in a state of use;
FIG. 33 is a top plan view thereof;
FIG. 34 is a three-quarter perspective view of a twelfth embodiment of a nasal dilator;
FIG. 35 is a perspective view thereof, shown in a state of use;
FIG. 36 is a top plan view thereof;
FIG. 37 is a three-quarter perspective view of a thirteenth embodiment of a nasal dilator;
FIG. 38 is a perspective view thereof, shown in a state of use;
FIG. 39 is a top plan view thereof;
FIG. 40 is a three-quarter perspective view of a fourteenth embodiment of a nasal dilator;

FIG. 119 is a perspective view thereof, shown in a state of use;

FIG. 120 is a top plan view thereof;

FIG. 121 is a three-quarter perspective view of a forty first embodiment of a nasal dilator;

FIG. 122 is a perspective view thereof, shown in a state of use;

FIG. 123 is a top plan view thereof;

FIG. 124 is a three-quarter perspective view of a forty second embodiment of a nasal dilator;

FIG. 125 is a perspective view thereof, shown in a state of use;

FIG. 126 is a top plan view thereof;

FIG. 127 is a three-quarter perspective view of a forty third embodiment of a nasal dilator;

FIG. 128 is a perspective view thereof, shown in a state of use;

FIG. 129 is a top plan view thereof;

FIG. 130 is a three-quarter perspective view of a forty fourth embodiment of a nasal dilator;

FIG. 131 is a perspective view thereof, shown in a state of use; and,

FIG. 132 is a top plan view thereof.

The long-dashed broken lines showing human facial features is directed to environment and form no part of the claimed design. The short-dashed broken lines illustrate portions of the nasal dilator that form no part of the claimed design.
